Friedrich LLP(57) **CLAIM**

The ornamental design for a combined robot and display, as shown and described.

DESCRIPTION

FIG. 1 is a perspective view of a combined robot and display showing my new design;

FIG. 2 is a front elevational view thereof, a rear elevational view thereof being a mirror image;

FIG. 3 is a left side elevational view thereof, a right side elevational view thereof being a mirror image; and,

FIG. 4 is a top plan view thereof.

Portions in broken lines illustrating portions of the combined robot and display form no part of the claimed design. Dot-dash broken lines defining boundaries of the claimed design form no part of the claimed design.
